UNITED STATES PATENT OFFICE.

JOHN W. GREEN, OF LOS ANGELES, CALIFORNIA.

DESIGN FOR A BADGE.

40,237.

Specification for Design. Patented Aug. 31, 1909.

Application filed June 29, 1909. Serial No. 505,088. Term of patent 14 years.

To all whom it may concern:

Be it known that I, JOHN W. GREEN, a citizen of the United States, residing in Los Angeles, in the county of Los Angeles and State of California, have invented a new, original, and ornamental Design for Badges, of which the following is a specification, reference being had to the accompanying drawing, forming a part thereof.

The figure is a front face view of a badge, illustrating my new design.

I claim:

The ornamental design for a badge, as shown.

JOHN W. GREEN.

Witnesses:

I. O. HOLLY,

A. H. SPENCER.
